UNITED STATES PATENT OFFICE.

RAYMOND B. GILLETTE AND RALPH W. HUTCHENS, OF EAU CLAIRE, WISCONSIN.

DESIGN FOR A TIRE-TREAD.

56,918.

Specification for Design.

Patented Jan. 18, 1921.

Application filed April 19, 1920. Serial No. 375,175. Term of patent 14 years.

To all whom it may concern:

Be it known that we, RAYMOND B. GILLETTE and RALPH W. HUTCHENS, citizens of the United States, and residents of the city of Eau Claire, in the county of Eau Claire and State of Wisconsin, have invented a new, original, and ornamental Design for a Tire-Tread, of which the following is a specification, reference being had to the accompanying drawings, forming a part thereof.

On the drawings:

Figure 1 is a developed plan view of a tire tread showing our new design.

Fig. 2 is a transverse vertical section therethrough.

We claim:

The ornamental design for a tire tread as shown.

RAYMOND B. GILLETTE.
RALPH W. HUTCHENS.
